UNITED STATES PATENT OFFICE.

ARNOLD VON SCHRENK, OF ST. LOUIS, MISSOURI.

REMOVABLE RUNNING-BOARD FOR AUTOMOBILES.

1,310,973.

Specification of Letters Patent. Patented July 22, 1919.

Application filed May 1, 1916. Serial No. 94,634.

To all whom it may concern:

Be it known that I, ARNOLD VON SCHRENK, a citizen of the United States, residing at the city of St. Louis, State of Missouri, have 5 invented a certain new and useful Improvement in Removable Running-Boards for Automobiles, of which the following is a full, clear, and exact description, such as will enable others skilled in the art to which it applies 10 pertains to make and use the same, reference being had to the accompanying drawings, forming part of this specification, in which—

Figure 1 is a cross sectional view of my improved running board for automobiles.

15 Fig. 2 is a side elevational view of one end of the same.

Fig. 3 is a plan view, partly broken away.

This invention relates to a new and useful improvement in running boards for automobiles, the object being to mount the board in such manner, on its support, that it will be easily and quickly detachable for various purposes, such for instance as to form a plank in extricating the car out of mud 20 holes, ditches, etc.; to form a bridge over otherwise impassable and dangerous spots; runways for curbs, platforms, banks, etc.; providing foundation for jacks in soft and muddy roads; providing flooring for working under the car; providing means for 25 forming a table, bench, etc. for use at picnics; providing a platform to support the wheels and tires away from oily and greasy places, and also to narrow the width of the 30 car and make the bottom accessible in case of repairs.

With these objects in view, my invention consists in the construction and arrangement and combination of the several parts, all of 40 which will hereinafter be described or pointed out in the claims.

In the drawings I have shown one form of removable running board with which operates a specially devised attaching device 45 for holding the same in position. The board and its attaching devices are illustrated as preferred forms, but it is obvious that there are many other forms of boards and attaching devices which could be used in carrying 50 out the principles of my invention.

In the drawings, 1 indicates the running board, which may be either of metal or wood, and faced with rubber or not as is well known in the art. 2 indicates reinforcing 55 angles arranged along the under side edges of the board to give the same strength and

stiffness. Other forms, such as channels, I beams, etc., could be used, if desired. 3 indicates a supporting bracket secured to the chassis of the car, this bracket consisting of 60 a vertical member which is designed to be secured to the chassis in any suitable manner and a horizontally disposed member for supporting the running board. There may be two or more brackets on each side of the 65 car for supporting the running board.

In order to hold the inner edge of the board in position, I provide the vertical member of the supporting bracket 3 with a stud 4 which stud is designed to be received in an opening in the vertical flange of the strengthening member 2 and an anti-rattling spring washer 5 is arranged on the stud between the vertical member of the bracket and the strengthening member of the running board 70 so as to avoid noise as much as possible.

The outer end of bracket 3 which is shown in the form of an angle, but which may be of any desired form, preferably has the outer end of its horizontal flange upset or 80 formed with a shoulder 3^a against which the outer strengthening member 2 rests. The means for securing the outer edge of the board to the bracket comprises a yoke shaped member 6 whose free ends, or the upper end of whose vertical legs, are bent inwardly, as shown in Fig. 1, to engage with openings 2^a in the outer strengthening member 2. This yoke shaped member is substantially U-shaped and the lower cross bar 85 thereof forms a bearing for an operating handle 7 having a cam face 7^a formed thereon, which cam face, when the handle is bent inwardly, as shown by full lines in Fig. 1, is designed to coöperate with the lower face 90 of the horizontal flange of the bracket 3 and draw the U-shaped yoke and running board tightly in position. The hooked upset portion 3^a at the outer edge of the horizontal flange of the bracket 3 preferably extends 100 down slightly, as shown in Fig. 1, so as to prevent accidental displacement of the cam face on the operating handle in an outward direction. The handle is provided with a projection 7^b near its inner end which is 105 designed to be sprung into an opening 3^b formed in the vertical flange of the horizontal portion of the bracket 3 so as to hold the handle in its raised or locked position. The yoke 6 is constructed of such material and 110 so shaped as to permit this slight springing action of the handle.

The running board is preferably provided with two or more of these clamping devices 6—7 in its length, depending upon the number of supporting brackets 3, and when it is desired to remove the running board, the handles 7 are depressed, as shown by dotted lines in Fig. 1, when the running board can be instantly lifted off of its supporting brackets for use for any purpose desired.

10 The parts 6—7 are shown as being detachably connected to the running board and may therefore be separated from the board; or, if desired, the upper hooked portions of the U-shape yoke could be extended and 15 bent downwardly so as to retain the clamps in position on the board, if desired. I prefer, however, to have them separately mounted, for the reason that the running board is then free from all obstructions at 20 its sides and may be more advantageously and conveniently used in some of the illustrations of its use hereinbefore mentioned.

Having thus described my invention, what I desire to secure by Letters Patent is set 25 forth in the following claims.

I claim:

1. In a device of the character described, the combination of supporting brackets extending under the running board, a removable running board supported by said brackets and secured at its inner edge to said brackets by pin and socket connections, and manually operable means coöperating with the outer edge of said running board for 30 clamping it in position and enabling it to be entirely removed from its supporting brackets.

Copies of this patent may be obtained for five cents each, by addressing the "Commissioner of Patents, Washington, D. C."

2. In a device of the character described, the combination with supporting brackets extending under the running board, of a removable running board arranged upon said brackets and having longitudinally disposed reinforcing members at or near its inner and outer edges, means on the brackets for engaging the innermost reinforcing member to 40 removably hold the inner edge of the board in position, and manually operable means coöperating with the outermost reinforcing member and the outer end of the bracket for removably securing the outer edge of 45 said board to said bracket, and at the same time rendering effective the engagement between the innermost reinforcing member of the board and said bracket.

3. In a device of the character described, 50 the combination of supporting brackets extending under the running board, a removable running board carried thereby, studs on the brackets for engaging the openings in the inner edge of said running board to hold the same in position, and manually operable clamps coöperating with the outer edge of the running board and supporting brackets for holding said running board in position whereby its inner edge will engage said studs.

In testimony whereof I hereunto affix my signature in the presence of two witnesses, this 29th day of April, 1916.

ARNOLD von SCHRENK.
